(57) **CLAIM**

The ornamental design for a semiconductor wafer and susceptor heating as shown and described.

DESCRIPTION

FIG. 1 is a perspective view of a semiconductor wafer and susceptor heating showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross sectional view taken along line 8-8 in FIG. 2.

The broken lines are shown in the views for illustrative purposes only and form no part of the claimed design.
